Victor J. Evans

ATTORNEY.

UNITED STATES PATENT OFFICE.

JAMES A. FORREST, OF KANOPOLIS, KANSAS.

CLOTH-HOLDER.

1,324,656.

Specification of Letters Patent. Patented Dec. 9, 1919.

Application filed July 21, 1919. Serial No. 312,227.

To all whom it may concern:

Be it known that I, JAMES A. FORREST, a citizen of the United States, residing at Kanopolis, in the county of Ellsworth and

5 State of Kansas, have invented new and useful Improvements in Cloth-Holders, of which the following is a specification.

This invention relates to improvements in devices for securing a cloth or cover upon 10 an ironing board.

An object of the present invention is the provision of a device for securing an ironing board cloth in position and maintaining the same in a smooth condition without 15 tearing or damaging the cloth, the construction of the device allowing for shrinkage and stretching.

Another object is the provision of a device of this character, which is simple and 20 economical of construction and easily applied or removed.

Other objects and advantages of the invention will appear as the following description is read in connection with the accompanying drawings.

In the drawings:

Figure 1 is a bottom plan view of an ironing board with the invention shown in position for use.

30 Fig. 2 is an edge view of the device removed from the board.

Fig. 3 is a transverse sectional view on the line 3—3 of Fig. 1.

Referring to the drawings in detail, 35 wherein like characters of reference denote corresponding parts, the ironing board is indicated at 10 and the cloth or cover at 11. The invention which is designed to be removably secured to the cloth or cover 40 comprises end members 12 and 13 and intermediate members 18. Each of the end members 12 and 13 are of arcuate formation, conformed to the shape of the end of the board, to which they are 45 secured, the end member 12 being of the greatest diameter is preferably provided with a brace 14. The device is preferably cut or otherwise formed from sheet metal, and both of the end members 12 and 13 50 have pivotally secured thereto, as indicated at 15, side arms 16. The end members and arms are provided with laterally extending prongs 17, for removable engagement with the ironing board cloth and by means of 55 which the device is held in position.

It is preferred to make the arms 16 com-

paratively short in length and to provide for engagement with the cloth at points between these arms, intermediate members 18. These members are also formed of thin 60 metal and are provided with prongs 19, smaller than the prongs 17 previously mentioned.

The members 14 are connected by means of chains 20, one end of which is connected to a link 21. This link is also connected through the medium of a flexible link connection 22 with the arms 16 and end member 13, while the arms 16 of the opposite member 12 are connected to one another by 70 means of links 23. These last mentioned links are connected to the link 21 through the medium of a spring 24, one end of which engages the chain 20. The opposite end of the spring 24 is adapted for removable 75 engagement with one end of a number of links 25, which connect with the links 23. The chain 20 passes over rollers 26, which are carried by the link 21.

From the foregoing description and accompanying drawings it will be apparent that the members 12, 13 and 14 may be connected to the ironing board cloth and the latter smoothly and tightly adjusted by engaging the end of the chain 20 with one 85 of the links 25, the resilient end of this connection permitting of shrinkage of the cloth without tearing.

The invention is susceptible of various changes in its form, proportions and minor 90 details of construction and the right is herein reserved to make such changes as properly fall within the scope of the appended claims.

Having described the invention, what is 95 claimed is:

1. A device for holding a cloth upon an ironing board and comprising end members adapted to be positioned at opposite ends of the board, inwardly extending pivoted 100 arms carried by said end members, means carried by the end members and pivoted arms for engagement with the cloth and means whereby the end members may be drawn longitudinally of the board and the pivoted 105 arms moved inwardly to stretch or tighten the cloth and hold the same in position.

2. A device for holding a cloth upon an ironing board comprising end members adapted to be positioned at opposite ends 110 of the board, intermediate members located between the end members at the opposite

- side edges of the board, inwardly extending arms pivoted to the end members, means carried by all of said members and arms for engagement with the cloth and means whereby said members and arms may be drawn inwardly to stretch or tighten the cloth and hold the same in position.
3. A device for holding a cloth upon an ironing board and comprising end members adapted to be positioned at opposite ends of the board, inwardly extending pivoted arms carried by said end members, hooks carried by said end members and arms for engagement with the cloth and means whereby the end members may be drawn longitudinally of the board and the pivoted arms moved inwardly to stretch or tighten the cloth and hold the same in position.
4. A device for holding a cloth upon an

ironing board comprising end members 20 adapted to be positioned at the opposite ends of the board, inwardly extending pivoted arms carried by said end members, intermediate members located between the end members at the opposite side edges 25 of the board, means carried by all of the said members and arms for engagement with the cloth and a link having a flexible connection with the intermediate members and the pivoted arms of one end member and 30 an adjustable yielding connection with the pivoted arms of the other end member, whereby said members may be drawn inwardly to stretch or tighten the cloth and hold the same in position.

35 In testimony whereof I affix my signature.

JAMES A. FORREST.
